UNITED STATES PATENT OFFICE.

VIRGEL B. STURTSMAN, OF ELWOOD, INDIANA.

CAR-DOOR.

1,291,240.

Specification of Letters Patent. Patented Jan. 14, 1919.

Application filed July 15, 1918. Serial No. 245,067.

To all whom it may concern:

Be it known that I, VIRGEL B. STURTSMAN, a citizen of the United States, residing at Elwood, in the county of Madison and State 5 of Indiana, have invented certain new and useful Improvements in Car-Doors, of which the following is a specification.

This invention relates to car doors for railway cars of the box type used chiefly for 10 hauling grain, fertilizer, and like commodity in bulk, the purpose being to provide a sectional door which admits of the sections being successively closed or opened as the car is loaded or unloaded.

15 The invention has for its primary purpose to facilitate the loading and unloading of railway cars and to reduce the labor incident to such work to the smallest amount possible.

20 The invention has for its object chiefly to provide a sectional door in which the sections are arranged one above the other so that when loading a car the sections may be moved into closed position as the car fills, 25 thereby avoiding unnecessary lift of the material. Conversely when unloading the car the sections are successively drawn aside as the car is unloaded thereby preventing any waste of material because the lower portion of the door-way remains closed until 30 the level of the material justifies moving the proper section so as to expose more of the door space.

The drawing illustrates a preferred embodiment of the invention; however, it is to be understood that in adapting the same to meet different conditions, various changes in the form, proportion, and minor details of construction may be resorted to without departing from the nature of the invention as 40 claimed hereinafter.

In the drawings:

Figure 1 is a side view of part of a box car provided with a sectional door embodying the invention,

Fig. 2 is a vertical section on the line 2—2 of Fig. 1, looking to the right,

Fig. 3 is a detail view of a portion of one of the door sections and the parts coöperating therewith,

Fig. 4 is a detail view of a portion of the upright showing a supporting roller, and

Fig. 5 is a detail perspective view of parts of the threshold strip. 55

Corresponding and like parts are referred to in the following description and indicated in the several views of the drawing by like reference characters.

The numeral 1 designates part of the side 60 of a box car provided with a door opening 2. The door for closing the opening 2 comprises a plurality of like sections A. These sections are arranged one above the other with edge portions overlapped so as to maintain close joints which prevent any escape 65 of material. It is to be understood that the door may comprise any number of sections and the latter unitedly close the door opening 2 when all the sections are moved into 70 closed position. Each of the sections A will be provided with fastening means of any nature so that when the sections are closed they may be secured against casual opening.

The door sections A may be constructed 75 of any material but it is preferred to form the same of sheet metal of proper gage. The door sections A have longitudinal portions pressed laterally in opposite directions to form ribs 3 and 4 which are hollow, the 80 spaces constituting grooves or ways for receiving supporting and directing elements. The ribs 3 and 4 likewise stiffen the sections thereby enabling the same to be constructed of material of relatively light gage. The 85 door sections may be constructed in any manner and while it is preferred to have the sections of uniform width, nevertheless the widths may vary if found most advantageous. The door sections A are slideable longitudinally and move between uprights 5 and 6 which are spaced apart a distance to admit 90 of the sections moving freely between them.

The door sections are supported and maintained in proper position by rollers 7 and 95 cleats 8. The cleats 8 are secured to the inner face of the upright 6 and are positioned to enter the grooves or ways formed in the hollow sides of the ribs 4. The rollers 7 are mounted upon the upright 5 and are 100 positioned so as to enter the grooves or ways formed in the hollow sides of the ribs 3. The upper edge portions of the door sections are offset so that the edges of the overlapping portions abut against shoulders 105 formed by lateral offset parts of the sec-

tions. This results in maintaining close joints and also in having the door sections mutually support one another in addition to the supporting and guiding means 7 5 and 8.

A threshold strip 9 is secured to the floor of the car in line with the door opening 2 and is provided with a groove 10 in its upper side to receive the lower edge of the 10 lowermost door section, whereby the close joint is maintained. A plate 11 is secured to the lower side of the transom of the door openings and an edge portion is bent so as to overlap the upper edge portion of the top- 15 most door section.

In operation as the car is loaded the door sections are successively drawn into closed position, thereby obviating the necessity for unnecessary lifting of the material. When 20 unloading the car the door sections are successively moved into open position from top to bottom, thereby preventing any waste of material and likewise avoiding unnecessary lifting. It will thus be understood the car 25 may be loaded and unloaded with a minimum amount of labor being expended.

Having thus fully described my invention, what I claim as new and desire to secure by Letters Patent is:—

30 1. A door, comprising a plurality of longitudinally slidable sections having the longitudinal edge portions of adjacent sections

overlapping, one of the overlapping edge portions being offset and forming a shoulder which engages the edge of the companion 35 overlapping edge portion, and each of the sections having grooves pressed laterally therefrom in opposite directions, and supporting elements engaging the said grooves.

2. A door, comprising a plurality of longitudinally slidable sections having their adjacent longitudinal edge portions overlapping, one of the overlapping edges being offset to provide a shoulder which engages the edge of the companion overlapping edge 45 portion, and each of the sections having grooves pressed laterally therefrom in opposite directions, one of the laterally pressed portions forming a shoulder to engage the edge of the offset overlapping portion of the adjacent section, uprights upon opposite sides of the sections, strips secured to one of the uprights and engaging the grooves in one side of the respective sections, and rollers mounted on the other upright and engaging the grooves in the sides of the sections.

In testimony whereof I affix my signature in presence of two witnesses.

VIRGEL B. STURTSMAN.
